Patented July 13, 1915.

UNITED STATES PATENT OFFICE.

OSCAR M. SHANNON, OF NEW YORK, N. Y.

FILE-CABINET.

1,146,738.

Specification of Letters Patent. Patented July 13, 1915.

Application filed May 13, 1914. Serial No. 838,213.

To all whom it may concern:

Be it known that I, OSCAR M. SHANNON, a citizen of the United States, residing at the city of New York, in the borough of Manhattan and State of New York, have invented certain new and useful Improvements in File-Cabinets, of which the following is a full, clear, and exact description.

This invention relates to improvements in filing cabinets and the like adapted for use by architects, engineers and construction firms, for filing drawings and plans where it is desirable to have a file cabinet of moderate size which may readily be moved from place to place.

In my patent for a drier cabinet, No. 1,010,694, I disclose a stationary cabinet comprising rack-sections, each section of which is supported by rollers from beneath, one pair resting upon the floor and the others upon a trackway supported by the casing of the cabinet. This type of cabinet presents many desirable features for use in architects' offices and the like, but where moderate-sized cabinets are to be used, it is desirable to mount the same so that they may be conveniently moved from place to place.

It is therefore the object of my invention to provide a construction whereby the front rollers which are adapted to rest on the floor in the open position of the sections will be supported off the same when the sections are in their closed position, whereby the rollers supporting the cabinet as a whole may come into play for moving the cabinet without interference from the rollers on the sections, and thus better adapting this type of cabinet for the purposes above stated.

With this object in view, my invention consists in the features of construction and combinations as hereinafter set forth and claimed.

In the drawings, Figure 1 is a side elevation of my improved cabinet with a portion of the casing removed, showing in dotted lines one of the sections pulled out or extended; Fig. 2 is a front elevation with portions shown in section; Fig. 3 is a detail of the support; and Fig. 4 is a section on the line 4—4 of Fig. 3.

Referring to the drawings, I have shown for the purpose of illustration a cabinet substantially similar to the one shown and described in Letters Patent above referred to, but it is not my intention to be limited to

this particular construction as the supporting means is equally applicable to all forms of cabinets of this general type.

The cabinet 1 made of a size convenient for readily removing it from place to place, is of sufficient height, width and depth to receive a number of rack-sections 2. These sections conform to the construction shown in my previous patent in many particulars but instead of the rack-bars for securing the proper rigidity of the front and rear walls of the sections, I provide a series of trays 3 made of perforated sheet metal adapted to form convenient receptacles for rolls of blueprints, tracings and the like, and which have the additional function of acting as braces to secure the necessary rigidity between the front and rear walls of the rack-sections. These rack-sections are provided with rollers 4 and 5 beneath the front and rear ends, respectively. The rollers 5 at the rear ends of each rack-section are constructed of a single piece of material with the middle portions thereof grooved to form a double roller with rolling surfaces at each end. The roller 4 at the front end of the section may be formed similar to those at the rear end or of any other desirable contour. Preferably they may be provided with rubber tires to eliminate any noise which may be occasioned by the pulling out of a section over a rough floor-surface. Arranged on a platform or false bottom 6 are a series of parallel strips 7 of a width slightly less than the groove in the rear roller. These strips form tracks for the respective rollers 5, the two rolling surfaces of the roller straddling the strip and being guided thereby. This makes it practically impossible for the rack-sections to get out of position and interfere with each other as they are being drawn out of or pushed into the cabinet.

The cabinet 1 is supported near its four lower corners by rollers 8 which are of the usual swivel type and comprise rollers 9 revolvably mounted in posts 7' which are rotatably mounted in sockets 10. The sockets 10 at the rear end of the cabinet are mounted on a plate 11 which is fastened to the false bottom or platform 6. Fastened underneath and parallel to the front edge of the platform and extending the entire distance between the side walls of the cabinet is the support 12. This support comprises a section 13 resting flat against the platform 6 and is fastened thereto by the fastening

means which pass through the socket 10 of the front set of rollers. A depending section at right-angles to the section 13 connects the same with a third section 14 which 5 is parallel to section 13 and located in close proximity to but without touching the floor. The section 14 which is in the nature of a shell, extends forwardly a short distance beyond the front edge of the platform and 10 is beveled at its outer edge as at 15, to allow the front rollers of each of the rack-sections to easily mount thereon as the section is being pushed into closed position. The portion 16 adjacent the beveled part slopes 15 downwardly to an arc-shaped groove 17 formed in the plate parallel to the front edge of the platform and at a distance therefrom sufficient to allow the front rollers of each of the rack-sections to rest therein 20 when these sections are in closed position. By making the portion 16 adjacent the groove downwardly-sloping, it will be seen that after the rollers of the rack-sections pass over the beveled portion, the rack- 25 sections will then have a tendency to continue their movement toward closed position by the force of gravity and on reaching the groove 15, will drop into the same and be retained thereby in the closed position. By 30 providing this downwardly-sloping portion leading to groove 17, it is apparent that after the rollers have passed over the beveled portion 13 and are seated in the groove 17, the rebound due to the hasty closing of a 35 section will be unlikely to carry the rollers out of the groove 17 and up the sloping portion 16. The rack-section if partially dislodged in this manner would then resume its closed position by the force of gravity and 40 the necessity for carefully closing the rack-sections by hand is thereby obviated, it being of course desirable to keep the rack-sections completely closed to prevent the accumulation of dust and dirt on the plans and files. 45 Having thus described my invention, I claim:-

1. A file cabinet of the class described, comprising a casing having its bottom raised

from the floor and supporting rollers beneath the same, a rack section slidably mounted in the said casing and having a supporting rear roller adapted to ride on said bottom and a supporting front roller extending below said bottom and adapted to ride on the floor when said section is being 50 opened and closed, and a support carried by said casing arranged in close proximity to the floor and adjacent its lower front edge, upon which said front roller is adapted to rest when said rack section is in closed po- 60 sition.

2. In a storage cabinet of the class de- 65 scribed, a rack-section having movable sup- porting means adapted to rest on the floor when the section is in open position, a sup- port for maintaining said supporting means off the floor when the section is in closed position, said support comprising a plate in close proximity to the floor, the outer por- 70 tion of said plate being beveled to permit the movable supporting means to readily pass thereover, and means on said plate for engaging with said supporting means for holding the rack-sections in closed position.

3. In a storage cabinet of the class de- 75 scribed, a rack-section having movable sup- porting means adapted to rest on the floor when the rack-section is in open position, a support for maintaining said supporting means off the floor when the section is in 80 closed position, said support comprising a plate in close proximity to the floor having a beveled portion at its outer end to permit the supporting means to readily pass onto said plate, a downwardly-inclined portion 85 adjacent the beveled portion, a groove in said plate adjacent the downwardly-inclined portion, said supporting means engaging with said groove when the rack-section is in closed position.

In witness whereof, I subscribe my signature, in the presence of two witnesses.

OSCAR M. SHANNON.
